(57) **CLAIM**

The ornamental design for the refillable napkin dispenser, as shown and described.

DESCRIPTION

FIG. 1 is a partially elevated, angled view of the refillable napkin dispenser.

FIG. 2 is a front view of the refillable napkin dispenser shown in FIG. 1.

FIG. 3 is a side view of the refillable napkin dispenser shown in FIG. 1.

FIG. 4 is a back view of the refillable napkin dispenser shown in FIG. 1.

FIG. 5 is a top view of the refillable napkin dispenser shown in FIG. 1; and,

FIG. 6 is a bottom view of the refillable napkin dispenser shown in FIG. 1.
